United States Patent Office

Des. 205,921

Patented Oct. 4, 1966

205,921

SKI BOOT CASE

Richard G. Woolworth, Lancaster, Pa., assignor to Old
Pal, Inc., Lititz, Pa.

Filed Sept. 2, 1965, Ser. No. 86,812

Term of patent 3½ years

(Cl. D87—5)

FIG. 1

FIG. 2

FIG. 3

FIG. 1 is a front elevational view of the ski boot case showing my new design.

FIG. 2 is a left side elevational view thereof, the right side being substantially a mirror image thereof; and

FIG. 3 is a top plan view thereof.

The rear, not shown, is substantially flat and unornamented.

I claim:

The ornamental design for a ski boot case, as shown and described.
